UNITED STATES PATENT OFFICE.

GEORGE W. PROUTY, OF ROSLINDALE, MASSACHUSETTS, ASSIGNOR TO TERKELSEN MACHINE COMPANY, OF BOSTON, MASSACHUSETTS, A CORPORATION OF MASSACHUSETTS.

DRIVING MECHANISM FOR WRAPPING MACHINES AND THE LIKE.

Original application filed June 21, 1921, Serial No. 479,410, and in Great Britain February 5, 1924.

Divided and this application filed May 19, 1925. Serial No. 31,382.

This invention has for its object to provide improved means for applying, and for controlling the application of the power of a continuously running electric or other motor to mechanism intermittently driven thereby. While capable of many other uses, the invention is particularly applicable to machines for wrapping annular objects (such as automobile tires, coils of wire, etc.) 5 of the type disclosed in my Letters Patent No. 1,542,474 issued June 16, 1925, of which this case is a division.

The more particular objects of the invention, together with means whereby the same 15 may be carried into effect, will best be understood from the following description of one form or embodiment thereof illustrated in the accompanying drawings. It will be understood, however, that the particular 20 construction and arrangement described and shown has been chosen for illustrative purposes merely, and that the invention, as defined by the claims hereunto appended, may be otherwise practised without departure 25 from its spirit and scope.

In said drawings:

Fig. 1 is a front elevation of the complete machine.

Fig. 2 is a side elevation, looking from 30 the right in Fig. 1.

Fig. 3 is a section taken substantially on the line 3—3, Fig. 1.

The frame of the machine herein shown 35 comprises a base 15 and a yoke 16, which is pivotally mounted on a shaft 17 journalled in an upright 18 rising from the base 15. The yoke 16 is provided with guide rollers 19 for an annular shuttle 20, which is rotated by a driving member in the form of a 40 friction disk 21 secured to the shaft 17 and driven through connections hereinafter more fully described from an electric motor 23. The tire or other work W to be wrapped is held by a weighted roller 14 45 upon work supporting rollers 24 which are driven through suitable connections from the driving member 21, the arrangement being such that the work W will be turned relatively slowly with respect to the speed of 50 rotation of the shuttle 20. Said shuttle is

formed with a hinged segment 26 normally closing a gap through which the work W may be inserted, while the yoke 16 may be adjusted about the axis of the shaft 17 to center the shuttle 20 with respect to annular objects of different sizes, said yoke being counterbalanced by a spring 27 and being locked in adjusted position by means of a clamp 28 carried by an upright 29 rising from the base 15. 55

The wrapping material, preferably in the form of a continuous strip S of paper, is supplied from a roll 30 supported by a reel or spindle 31 carried by the yoke 16. Said paper passes from the roll 30 over a guide 60 plate 34 to the shuttle 20 which is provided with an annular flange 35 about which the strip S is wrapped as the shuttle is rotated and from which said strip is led to the work W. Between the shuttle and the 65 source of supply 30, there is provided a cutting mechanism comprising a knife 37 co-operating with a portion of the guide plate 34 to sever the strip S, when a sufficient length thereof has been wound around the 70 shuttle flange 35 to complete the wrapping 75 of the work W. The knife 37 is automatically actuated, after a predetermined number of rotations of the shuttle, by a counting mechanism 38 actuated at each rotation 80 of said shuttle by a cam projection 39 thereon, said counting mechanism being manually adjustable in accordance with the size 85 of the articles wrapped.

From the foregoing, the nature, location, 90 and function of the parts referred to will be sufficiently understood for the purposes of the present case. With the exception of those hereinafter described, and in so far as the others enter into combination therewith, 95 as pointed out in the claims, these parts are not involved in the present invention and may be of any suitable construction and arrangement.

The disk or driving member 21 is driven 95 by frictional engagement therewith of a friction wheel 40 on the shaft 41 of the motor 23. The said motor is carried by a frame 42 which normally rests by gravity on the top of the base 15, in which position the fric- 100

tion wheel 40 is out of engagement with the driving member or disk 21. In order to connect these parts to start the machine, the frame 42 and the motor 23 are moved or 5 lifted bodily so as to bring said wheel 40 into engagement with the disk 21. To this end the following connections are provided:

The base 15 has secured thereto a plate 43 having depending ears 44 which extend 10 downwardly through an opening in the top of said base. Journalled in the ears 44 is a shaft 45 having secured thereto arms 46, the opposite ends of which are pivoted at 47 to depending ears 48 formed on the motor 15 frame 42. Between the lower ends of the depending ears 44 and 48 are link connections 49 forming, with the arms 46 and ears 44 and 48, a parallel link motion, whereby 20 when the shaft 45 is oscillated a vertical movement is imparted to the motor frame 42 substantially in a straight line. The shaft 45 has secured thereto a third arm 50, which, with said shaft and the arms 46 thereon, constitutes a lifting lever for the 25 motor. The forward end of the lever 50 is connected by links 51 with the lower end of a starting or actuating lever 52 pivoted at 53 and having at its upper end a handle 54 by which said actuating lever may be moved 30 about its pivot 53 to cause the motor 23 to be lifted until the friction wheel 40 is brought into frictional engagement with the driving wheel 21, thereby causing the rotation of the shaft 17. The arms 46 and 50 and the shaft 45 form, in effect, a bell crank 35 lever pivoted intermediate its ends, it being obvious that the longer arm 50 of the lever might be in alignment with the shorter arms 46 but is offset therefrom as shown in the 40 drawings, for convenience in operating the machine.

As shown in the drawings, the motor 23 is in raised position with the friction wheel 40 thereof contacting with the driving wheel 21, and the links 51 are in alignment with 45 the actuating lever 52, thereby preventing the lowering of said motor 23 and thus causing the machine to be operated until the handle 54 is moved to the right in Fig. 3 of the drawings, thus breaking the toggle connection 51, 52 and permitting the motor 23 to return to its normal lowered position by gravity.

The pivot 53 for the actuating lever 52 is 55 eccentrically mounted in the bearing 55 and has secured to one end thereof a quadrant 56 having a slot 57 therein through which a clamping bolt 58 is adapted to extend into the bearing 55 to lock the eccentric pivot 53 60 in adjusted position.

By means of this construction the pivot for the actuating lever 52 may be nicely adjusted so that in the lifting of the motor 23 the alignment of the actuating lever 52 65 and the toggle links 51 will be assured as

soon as the friction wheel 40 comes into sufficient frictional contact with the driving wheel 21.

Having thus described my invention, I claim:

1. The combination with mechanism to be driven, said mechanism having a driving member, of a motor, a friction wheel carried thereby and normally removed from said driving member, an arm pivoted intermediate its ends and having one end pivotally connected to the supporting frame of said motor, a pivoted actuating lever, and a toggle link connecting said actuating lever with the opposite end of said arm. 70 75 80

2. The combination with mechanism to be driven, said mechanism having a revoluble driving member, of a motor, a revoluble friction wheel carried thereby and normally removed from said driving member, an arm pivoted intermediate its ends and having one end pivotally connected to the supporting frame of said motor, a pivoted actuating lever connected to the opposite end of said arm, and means whereby the position of the lever pivot may be adjusted. 85 90 95

3. The combination with mechanism to be driven, said mechanism having a revoluble driving member, of a motor, a revoluble friction wheel carried thereby and normally removed from said driving member, an arm pivoted intermediate its ends and having one end pivotally connected to the supporting frame of said motor, a pivoted actuating lever connected to the opposite end of said arm, and means for insuring the parallelism of the several positions of the axis of the motor while being lifted. 100 105 110

4. The combination with mechanism to be driven, said mechanism having a revoluble driving member, of a motor, a revoluble friction wheel carried thereby and normally removed from said driving member, an arm pivoted intermediate its ends and having one end pivotally connected to the supporting frame of said motor to lift the same and cause said friction wheel to engage said driving member, and a link mechanism for insuring the parallelism of the several positions of the axis of the motor while being lifted. 115 120 125

5. The combination with mechanism to be driven, said mechanism having a revoluble driving member, of a motor, a revoluble friction wheel carried thereby and normally removed from said driving member, an arm pivoted intermediate its ends and having one end pivotally connected to the supporting frame of said motor, a pivoted actuating lever operatively connected with the opposite end of said arm, and an eccentric for adjusting the position of the lever pivot. 130

6. The combination with mechanism to be driven, said mechanism having a revoluble driving member, of a motor, a revoluble fric-

tion wheel carried thereby and normally removed from said driving member, an arm pivoted intermediate its ends and having one end pivotally connected to the supporting frame of said motor, a pivoted actuating lever operatively connected with the opposite end of said arm, an eccentric for

adjusting the position of the lever pivot, a slotted quadrant on said eccentric, and a clamping bolt cooperating with said quadrant to lock said eccentric. 10

In testimony whereof I affix my signature.

GEORGE W. PROUTY.
